UNITED STATES PATENT OFFICE

126,478

DESIGN FOR A SHOE

William Lipp and Frank Hirsch, New York, N. Y.

Application November 16, 1940, Serial No. 96,633

Term of patent 3½ years

To whom it may concern:

Be it known that we, William Lipp and Frank Hirsch, both citizens of the United States, residing at New York, county of the Bronx, State of New York, respectively, have invented a new, original, and ornamental Design for a Shoe, of which the following is a specification, reference being had to the accompanying drawing, forming part thereof, wherein—

Fig. 1 is a top plan view of a shoe, showing my new design;

Fig. 2 is a side elevational view thereof; and Fig. 3 is an enlarged fragmentary view of the toe portion of the shoe, as shown in Figures 1 and 2.

We claim:

The ornamental design for a shoe, substantially as shown.

WILLIAM LIPP.
FRANK HIRSCH.
